US0D1020626S

(12) **United States Design Patent** (10) Patent No.: **US D1,020,626 S**
(45) Date of Patent: ** Apr. 2, 2024

(54) **WIRELESS CHARGER**

(71) Applicant: **Shenzhen Yifeng Intelligent Technology Co., Ltd.**, Shenzhen (CN)

(72) Inventor: **Ning Liu**, Shenzhen (CN)

(**) Term: **15 Years**

(21) Appl. No.: **29/835,973**

(22) Filed: **Apr. 22, 2022**

(30) **Foreign Application Priority Data**

Mar. 22, 2022 (CN) 202230151445.5

Assistant Examiner — Devin Kelly

(57) **CLAIM**

The ornamental design for a wireless charger, as shown and described.

DESCRIPTION

FIG. 1 is a front, top perspective view of a wireless charger, showing my new design;

FIG. 2 is a rear, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures illustrate portions of the wireless charger that form no part of the claimed design.

1 Claim, 8 Drawing Sheets
